UNITED STATES PATENT OFFICE.

CLINTON W. RAKER, OF SHAMOKIN, PENNSYLVANIA.

DESIGN FOR A HOOK.

SPECIFICATION forming part of Design No. 24,573, dated August 20, 1895.

Application filed July 10, 1895. Serial No. 556,577. Term of patent 7 years.

To all whom it may concern:

Be it known that I, CLINTON W. RAKER, of Shamokin, in the county of Northumberland and State of Pennsylvania, have invented 5 and produced a new and original Design for Garment-Hooks, of which the following is a full, clear, and exact description.

Reference is to be had to the accompanying drawings, forming a part of this specification, 10 in which—

Figure 1 is a side view of a hook embodying my new design, and Fig. 2 is an inverted plan view.

The leading feature of my design consists 15 in the arms *a* and *b*, of which the upper one is the longer, both arms having upturned outer ends and both presenting two members when viewed in side elevation, said arms *a* and *b*

being joined by a vertically-ranging curved member *c*, one member of each arm extending rearwardly beyond the curved member *c*, and the ends of said rearwardly-extending members being each bent first outwardly, as at *d*, and then rearwardly, as at *e*, the bends in each member being at the same side of 25 the hook.

A minor feature of the design is the forward inclination of the outward bends *d* and the rearward inclination of the inward bends *e*.

I claim—

The design for a garment hook, substantially as shown and described.

CLINTON W. RAKER.
